LAMP

George E. Peters, Miami, Fla.

Application March 26, 1954, Serial No. 29,709

Term of patent 7 years

(Cl. D48—20)

To all whom it may concern:

Be it known that I, George E. Peters, a citizen of the United States, residing at Miami, in the county of Dade and State of Florida, have invented a new, original, and ornamental Design for a Lamp, of which the following is a specification, reference being had to the accompanying drawing, forming a part hereof.

Figure 1 is a front elevational view of a lamp, showing my new design;

Figure 2 is a side elevational view thereof; and Figure 3 is a top plan view.

I claim:

The ornamental design for a lamp, as shown.
